UNITED STATES PATENT OFFICE

135,686

DESIGN FOR A HORIZONTAL BORING MILL

Frank S. Jones, Drexel Hill, Pa.

Application December 5, 1941, Serial No. 104,498

Term of patent 3½ years

To all whom it may concern:

Be it known that I, Frank S. Jones, a citizen of the United States and a resident of Drexel Hill, in the county of Delaware and State of Pennsylvania, have invented a new, original, and ornamental Design for a Horizontal Boring Mill, of which the following is a specification, reference being had to the accompanying drawing forming a part thereof.

Figure 1 is a front perspective view of a hori-

zontal boring mill showing my new design, and Figure 2 is a rear perspective view of the horizontal boring mill illustrated in Figure 1.

The right end elevational view of the boring mill, as illustrated in Figure 1, is substantially plain.

I claim:

The ornamental design for a horizontal boring mill, as shown and described.

FRANK S. JONES.
